UNITED STATES PATENT OFFICE

2,341,471

SNOW GRINDING DEVICE

William J. O'Brien, Boston, Mass.

Original application May 8, 1940, Serial No. 334,009. Divided and this application June 30, 1941, Serial No. 400,533

2 Claims. (Cl. 83—63)

This invention relates to a device to grind snow, and is a division of my pending patent application Serial No. 334,009, filing date May 8, 1940, which became Patent No. 2,261,732 on Nov. 4, 1941.

The principal object of my invention is to provide a device to rapidly break up snow, such as may be found in the street, into smaller particles. This makes it easier to melt. Another object is to so construct such a device that it can also dispose of foreign objects such as stones readily. A further object is to provide a rotatable funnel through which the ground snow can be discharged at different points. A still further object is to construct the driving means for said device so that a snow discharge funnel and the snow grinding means may be simultaneously operated from the same source of power.

The foregoing and other objects which will appear as the nature of the invention is better understood, may be accomplished by a construction, combination and operative arrangement of parts such as is disclosed by the drawings and specification. The nature of the invention is such as to render it susceptible to various changes and modifications, and, therefore, I am not to be limited to said disclosure but am entitled to all such changes therefrom as fall within the scope of my claims.

In the drawings:

Figure 1 is a side elevational view of my device the driving shaft being shown broken away.

Figure 2 is a sectional view showing details of the means for supporting and rotating the funnel into which the snow passes after being ground.

Figure 3 is a sectional view taken on the line 3—3 of Figure 5, showing more details of said means.

Figure 4 is a longitudinal sectional view of my snow grinding device.

Figure 5 is a sectional plan view taken on the line 5—5 of Figure 4.

As illustrated, my device has a receptacle 50 to receive snow, which is preferably cylindrical. The snow is ground within said receptacle by means of a rotatable grinder member having a vertical shaft 52 which is rotatably mounted in a base member 53 having ball bearings 54 therein, and which is bolted as at 55 to said receptacle 50. Mounted to said shaft 52 are horizontally extending grinding arms 56, the ones in the upper portion of said receptacle 50 preferably extending but a short distance laterally in opposite directions from said shaft 52, said arms 56 grad-

ually lengthening so that they extend farther towards the inner periphery of said receptacle 50 the farther down in said receptacle they are until about half way down they extend to a point adjacent said inner periphery. This arrangement leaves more space in the upper portion of said receptacle 50 for the snow to drop into unimpeded by said arms 56.

Extending across the interior of said receptacle 50 are stationary shear rods 58, there being four groups of these as shown in Figure 5 of the drawings, the rods in each group preferably extending at right angles to the rods in the groups next adjacent thereto, as illustrated in Figure 5 of the drawings. Said rods are so located that they leave considerable open space 59 in the middle of said receptacle 50 so that foreign objects such as stones, pieces of ice, etc., which cannot be ground up easily may drop through said open spaces and pass into said snow-melting tank. I preferably leave said open space 59 of greater width than the width of a said group of said rods 58, measuring the latter width from the periphery of said receptacle 50 inwardly. Also the upper said arms 56 are not long enough to span the entire space 59 so that in the upper portion of said receptacle there is clear space laterally between said grinding arms 56 and said shear rods 58. These stationary shear rods 58 may be in the form of flat steel blades or hard wire, and they are united or fastened to the sides of said receptacle 50. They are located from a point near the top of said receptacle most of the way down, being spaced from each other vertically about 1 inch, while said rotatable grinding arms 56 are spaced from each other vertically about 1 inch and are in different horizontal planes than said shear rods 58, so that said grinding arms and shear rods are spaced vertically less than $\frac{1}{2}$ inch apart. This distance apart may be varied considerably, depending somewhat upon the condition of the snow to be ground or pulverized. Said shear rods 58 and grinding arms 56 are preferably made of hard metal, and, therefore, could have sharpened edges although that is not necessary in order to grind or pulverize the snow to the desired degree of fineness.

Directly below said pulverizer-receptacle 50 and rotatably connected thereto is a rotatable snow-receiving funnel 60 which has an eccentric outlet or spout 61 at one side thereof, where snow will pass from said receptacle 50 through said funnel 60 outwardly at constantly changing points due to said eccentric outlet. Said funnel 60 is rotated by means of a large driven gear 63 which

has a depending portion 63a. Said gear 63 meshes with a pinion gear 64 that is driven by a vertical drive shaft 65 that can be rotated by any suitable source of power.

Said shaft 65 extends from said pinion gear 64 upwardly to a point where bevel gears 67 transmit the power from said shaft 65 to a horizontal shaft 68 and thence through bevel gears 69 to said grinder shaft 52, thereby rotating said shaft 52 that carries the grinding arms 56. Said horizontal shaft 68 is rotatably mounted in the outer wall of said receptacle 50 at two different places 69a and 70.

Fastened by screws 71 to said receptacle 50 at its lower extremity is a ring member or skirt 72 which serves as a support for said large gear 63 which latter completely encircles said receptacle 50. Said gear 63 is rotatably mounted on rollers 74 which are held in place by screws 75. Said rollers 74 travel on said skirt 72 thereby supporting said gear 63. This gear 63 is also centrally located by rollers 76 held in place by screws 77, which rollers roll against the outside periphery of said receptacle 50. This permits a rotative movement of the gear 63 with the least amount of friction. Said funnel 60 is fastened to said depending portion 63a of said gear 63 by bolts 78.

While it is not absolutely necessary to rotate said funnel 60, and it could be an integral part of said receptacle 50 in the event it was stationary, nevertheless its rotation is helpful inasmuch as it avoids piling up the snow in one place.

What I claim is:

1. A snow grinding device comprising a recep-

5 tacle, a shaft therein rotatably mounted, arms extending laterally from said shaft, rods of varying lengths supported at each of their ends by and extending laterally within said receptacle, and means operably connected to said shaft to cause rotation thereof, said rods being arranged in four groups around said receptacle at right angles to each other in plan view, the rod extending farthest inwardly towards the center in any group being spaced from the center and from the nearest rod in the directly opposite group sufficiently far to leave an open space in the middle of said receptacle that is wider than the width of any one group of said rods.

15 2. A snow grinding device comprising a cylindrical receptacle, a shaft coaxially rotatably mounted therein, arms extending laterally from said shaft at different points so as to be spaced apart vertically, rod members positioned close to the inside of the receptacle in chordal relation to the cylindrical wall thereof, the said rod members extending in substantially end to end relation and leaving a substantial open space around the rotor from top to bottom of the receptacle, the arms in the upper portion of said receptacle 20 terminating at a point spaced from the furthest inward portions of the rods to thereby leave a clear space in the upper portion of the receptacle and the arms in the lower portion of said receptacle terminating at a point substantially overlapping the inward portions of the rods and means for rotating the shaft to grind snow fed into the top of the receptacle.

WILLIAM J. O'BRIEN.
